UNITED STATES PATENT OFFICE.

JOSEPH L. HERZOG, OF NEW YORK, N. Y.

METHOD OF FORMING CUFF-BUTTONS.

1,170,064.

Specification of Letters Patent.

Patented Feb. 1, 1916.

Application filed April 30, 1913. Serial No. 764,547.

To all whom it may concern:

Be it known that I, JOSEPH L. HERZOG, a citizen of the United States, and a resident of New York, borough of Manhattan, in the county of New York and State of New York, have made and invented certain new and useful Improvements in Methods of Forming Cuff-Buttons, of which the following is a specification.

10 My invention relates to a method of making or forming cuff buttons, and more particularly to that style or type thereof commonly known as a link button, the object being to devise a method wherein such a 15 button may be formed of a single, continuous piece of filled gold, and in such a manner that that portion of the surface thereof which is exposed to view and wear will be entirely covered or protected by the previous metal.

In Letters Patent heretofore granted to me on December 20th, 1910, and numbered 979,163, I have illustrated and described a method of forming link cuff buttons particularly adapted for the production of the same from a single, continuous piece of gold or precious metal. This method, however, would not suffice for the production of the article from filled gold, in that it would 20 leave exposed to view portions of the base metal and thereby render the completed article unsightly in appearance. In carrying out my present method, all portions, or practically all portions, of the surface of the 25 article exposed to view and wear, are covered or protected by the precious metal forming a part of the filled stock, thereby lending to the completed button the appearance of being made of solid gold. The 30 results of the several steps of the method I have illustrated in the accompanying drawing, in which—

Figure 1 is a face view of a piece of filled stock, Fig. 2 representing a section thereof 45 on the line 2—2 of Fig. 1; Fig. 3 is a plan view of the article resulting from the first step in the process, and Fig. 4 a sectional view thereof taken on the line 4—4 of Fig. 3; Fig. 5 is a face view, Fig. 6 a sectional view taken on the line 6—6 of Fig. 5 and illustrating the button at another stage of its formation, and Fig. 7 representing a sectional view taken on the line 7—7 of Fig. 5; Figs. 8 and 9 are respectively plan and 50 sectional views showing the button at the next stage of its formation, the sectional view in Fig. 9 being taken on the line 9—9 of Fig. 8; Fig. 10 is a plan view showing the button at the next stage of formation; Fig. 11 a sectional view thereof taken on the line 11—11 of Fig. 10; Fig. 12 is a plan view showing the button at its next stage of formation; Fig. 13 is a plan view of the button shown in the next stage of its formation, that is, with the trimmed edges 55 turned up or cupped; and Fig. 14 is a sectional view thereof taken on the line 14—14 of Fig. 13; Fig. 13^a is an enlarged cross-sectional view taken through the post of the button in the stage of formation, as illustrated in Fig. 13, it being noted that one of the thin fins of metal, which extend from the post, is turned in against the post, so as to form a part thereof, while the other of the fins is left in its projected position, 70 for the purpose of illustration; Fig. 15 shows a plan view of the button in its next stage of formation, the side edges of the two plates being curled or bent over; and Fig. 16 a sectional view thereof taken on the line 80 16—16 of Fig. 15; Fig. 17 is an edge view of the finished button, showing the relative positions of the two plates to each other.

Referring to the drawings, it will be seen that I start with a piece of stock 20 provided with a rib 21, the latter ultimately forming the post or bar of the button. A theoretical disposition of the thin film of metal formed on the post 35, is illustrated in Fig. 13^a, wherein it will be apparent that the thin film is of such minute thickness as to be constituted almost entirely of precious metal. One of the thin films is turned up against the post, as at 35¹, so as to merge into the surface thereof, while the other is left in its extended position, for purposes of illustration. This piece of stock 20 is what is usually known and referred to as filled gold, by which is meant stock comprising an inner plate 22 of base metal and 100 outer plates 23 of precious metal, the stock being rolled down to the proper thickness, in accordance with the article to be made therefrom. In the several steps of the method or process of forming the button, I 105 utilize suitable dies, unnecessary to be herein illustrated, as the results of these several steps are clearly illustrated in the several figures of the drawings. From the piece of stock 20 I stamp or cut the blank 110 illustrated in Figs. 3 and 4, that is, a blank comprising the partially formed disks 24, 25,

connected by the thickened portion 26. This blank is then, by means of suitable dies, cut and pressed into the form as illustrated in Figs. 5 and 6, the stock being materially reduced in thickness and the disks 24—25 somewhat enlarged, the metal in the thickened central portion 27 being slightly curved upwardly, as illustrated in section in Figs. 6 and 7. It is to be understood that the term "disk" is used in its broad sense, and refers to an element not necessarily limited to circular configuration, but to an element of relatively thin material of square, oval, circular, or of any desired outline. The button thus partially formed is then given the shape as illustrated in Figs. 8 and 9, wherein the central portions 28 are given a further partial shape of the finished button, the central portion 29 being also partially formed into the shape of a post. The edges of this partially formed button are then cut or trimmed as illustrated in Figs. 10 and 11, a thin fin 30 being left connected with the post 31. The edges of the disks are then further trimmed as illustrated in Fig. 12, the disks 32 being given a further partial formation, the fin 33 being reduced in thickness until it results in a minute film of metal of practically no thickness whatever. By the next operation this thin film of metal is turned up against the post 35, Fig. 13, the edge of the film being represented by the line 35, Fig. 14, the edges 36 of the disks being at the same time turned upwardly, as also illustrated in said figure section in 14. By the next operation these edges are curled over as illustrated at 37 in Figs. 15 and 16, thereby hiding from view the raw edges of the stock, the button being then finished as illustrated in Fig. 17 by bending the two disks 38 at a proper angle to each other. By this method it will be understood that each and all portions of the surface of the button exposed to view and wear are covered or protected by precious metal, the raw edges of the stock forming the outer periphery of the disks being curled or bent under in order to hide them, the resulting button comprising the disks 38, being formed of comparatively thin metal, and the connecting post 39 of comparatively thick metal. This button when completed has practically the same appearance and finish as that patented to me on the 25th day of October, 1910, and numbered 973,864, and is possessed of all the characteristics thereof regarding strength and durability, but, by reason of

the material from which it is formed, can be manufactured and sold at a lower cost.

What I claim is:—

1. The method hereinbefore described of forming one-piece cuff buttons, comprising the partial formation from a ribbed blank of filled stock, of the two disks of metal from the thin portions of said blank, and 65 a connecting bar or post from the rib of said blank, the metal between said disks being removed adjacent the post and the resulting edge of said metal forced against the sides of said post, then curling the edges 70 of said disks over to conceal the extreme edges of the same, and finally bending said disks at an angle to each other.

2. The method hereinbefore described of forming cuff buttons from a single, continuous piece of metal, consisting in first cutting from a ribbed blank of filled stock the partially formed button, the thinner portions of said blank forming the disks, and the rib of said blank forming the connecting bar between said disks; secondly, completing the formation of the thickened connecting bar between said disks by removing the metal adjacent the same and turning the resulting edge against said bar, 85 then cupping and curling the outer edge of said disks to conceal the extreme edges thereof from view, and finally bending the disks at an angle to each other to form the completed button.

3. The method hereinbefore described of forming cuff buttons, comprising the partial formation of the disks from a single, continuous piece of filled ribbed stock, the disks being formed of the thinner portions 95 of said stock, and the connecting bar from the rib of said stock, reducing the thickness of the metal between said disks and adjacent said bar to less than that of the disks, removing this thin metal and pressing the 100 resulting edge against the sides of said bar, curling the outer edges of said disks to conceal the extreme edges thereof from view, and finally bending the disks at an angle to each other to form the completed button.

Signed at New York, borough of Manhattan, in the county of New York and State of New York, this 25th day of April, A. D. 1913.

JOSEPH L. HERZOG.
